UNITED STATES PATENT OFFICE.

HENRY WEBER, OF CHICAGO, ILLINOIS, ASSIGNOR TO LATHAM MACHINERY COMPANY, OF CHICAGO, ILLINOIS, A CORPORATION OF ILLINOIS.

WORK-GUIDE.

• 1,111,116.

Specification of Letters Patent. Patented Sept. 22, 1914.

Application filed February 7, 1912. Serial No. 676,090.

To all whom it may concern:

Be it known that I, HENRY WEBER, a citizen of the United States, residing at Chicago, in the county of Cook and State of Illinois, have invented certain new and useful Improvements in Work-Guides, of which the following is a specification.

This invention relates to improvements in work guides of the type shown and described in my application Serial No. 541,212, and which guide is particularly adapted though not necessarily limited in its use in connection with stitching or stapling machines of the type shown and described in my application Serial No. 541,209, for directing and insuring the proper positioning of the work with respect to the stitching or stapling mechanism, and to which applications reference may be had for a full understanding of the parts not specifically described herein.

One of the objects of the present invention is to provide an improved device of this class which may be readily attached to the machine and adjusted and held in various positions corresponding to the adjustment of the work support and the stitching mechanism.

A further object is to provide an improved device of this class which will be of sufficient rigid construction to prevent vibration thereof, but which will yield sufficiently under the action of the stitching or stapling mechanism.

To the attainment of these ends and the accomplishment of other new and useful objects, as will appear, the invention consists in the features of novelty in substantially the construction, combination and arrangement of the several parts hereinafter more fully described and claimed and shown in the accompanying drawings illustrating the invention, and in which—

Figure 1 is a front elevation of a portion of the stitching or stapling mechanism having an improved attachment constructed in accordance with the principles of this invention applied thereto, showing in full lines the attachment in one position and in dotted lines in another position. Fig. 2 is a right hand side elevation of the parts shown in Fig. 1. Fig. 3 is a top plan view as taken on line 3, 3, Fig. 1. Fig. 4 is a detail cross-sectional view of a portion of the work guide, showing the manner in

which the flaps of the work are overlapped. Fig. 5 is a side elevation of the work guide, having a part broken away. Fig. 6 is a top plan view of a detail. Fig. 7 is a top plan view of the parts shown in Fig. 5, with parts broken away. Fig. 8 is a side elevation of the guide proper, with parts removed.

Referring more particularly to the drawings and in the present exemplification of the invention, the numeral 10 designates generally a main support, to which is secured a work-supporting arm or member 11. This arm or member 11 is adapted to be adjusted laterally with respect to the support 10 in any suitable manner such as by means of an adjusting device 12, whereby the work-supporting arm may be positioned with respect to the stapling mechanism designated generally by the reference numeral 13 in Figs. 1 and 2.

All of the above mentioned parts may be of any desired construction and form no part of the present invention, but constitute the subject-matter of a separate application.

The work-supporting arm 11 in the present form of the invention has secured thereto table sections 14, the tops of which are substantially flush with the top of the arm 11, and the sections are provided with a plurality of bolt apertures 15, which are preferably formed in metallic strips 16 countersunk in the face of the table section so that their upper faces will stand substantially flush with the top of the table sections. These strips 16 are preferably arranged parallel with the arm 11 and on each side thereof. Similar strips 17, 18 may be provided and countersunk in the face of the table sections and so arranged to extend across the table sections and transversely with respect to the strips 16. A gage 19 is provided with rearwardly projecting arms or portions 20, which latter are provided with slots through which fastening devices 21 pass so as to engage the bolt apertures in the strips 16. This gage 19 extends transversely with respect to the arm 11, and may be adjusted longitudinally with respect to the arm by loosening the fastening devices 21. After adjustment, the gage may be secured in its desired position by tightening the fastening devices.

The work guide comprises spaced members 22, 23 arranged one above the other and

connected along one edge by an upright or web 24. The member 22 projects for some distance beyond the extremities of the member 23 and constitutes a work-supporting bar, the forward extremity 25 of which is preferably reduced laterally as shown in Fig. 7, and a clencher block 26 is carried by this portion 25. The other extremity of the bar 22 is enlarged laterally, as shown, to project beyond the outer face of the web 24, and the portion of the web 24 adjacent this enlarged portion of the bar 22 is deflected as at 27 to form an inclined guide for directing the work between the members 22, 23.

In machines of the type illustrated in the drawings the head 29^a which carries the stapling and stitching mechanism 13 is swiveled for movement in the outer terminal 29^b of the goose-neck or support 29, said outer terminal 29^b of said goose-neck being stationary. Though the head 29^a may have any number of adjustments, in the present exemplification of the machine, it is arranged to swing to three adjusted positions in order that the staple may be driven through the work at three different angles, dependent upon the class of work being operated upon.

The work guide heretofore described is supported by and attached to the outer terminal 29^b of the goose-neck 29 and therefore is stationary with respect to the movement of the head 29^a. As set forth more clearly in Fig. 2, the guide bar 22 is arranged transversely with respect to the arm or bar 11 and is always parallel to the gage 19, irrespective of the position of the bar 11 and the head 29^a. The lateral edge of this work supporting bar 22 adjacent to the gage 19 is beveled or inclined as at 28 in order that the work may be easily directed into the guide.

In order to mount the work guide heretofore described upon the outer terminal 29^b of the goose-neck, a horizontal work plate is secured to one side of the outer terminal 29^b by vertical bars attached to the inner end of the bracket plate 30, and secured to the outer terminal 29^b by suitable attaching means 31, the upper terminals of said bars being connected at a point adjacent the outer end of the bracket plate by a plurality of obliquely arranged braces. The guide is adjustably secured to the bracket plate 30 in such a manner that the guide is provided with three adjustments with respect to the bracket plate 30 in order that the same may be adjusted to conform with the various adjustments of the head 29^a, and at all times rest parallel to the gage 19 and project laterally and horizontally from the outer terminal 29^b of the goose-neck 29 in a direction similar to that of the bracket plate 30. This bracket plate 30 is provided with a series of apertures or openings 32, 33 and 34 arranged in pairs and spaced from each other longi-

tudinally with respect to the bracket plate 30. An intermediate bracket 35 constitutes the connection between the work guide heretofore described and the bracket plate 30, said intermediate bracket being provided with a horizontal head 35^a at its upper terminal and with a horizontally arranged portion at its lower terminal, which extends toward the stitching mechanism 13. This horizontally arranged portion of the intermediate bracket 35 is pivotally connected with the work guide through the medium of the pin 36 passing through a pair of uprights 37 mounted or formed upon the plate or web 23, said horizontal portion of the bracket 35 being retained between said uprights 37. In order to provide a limited pivotal movement about the pin 36, a slot 39 is formed in the terminal of the horizontal portion of the bracket 35 which engages a pin 38 arranged between the uprights 37, thus permitting the uprights 37 and the guide carried thereby to have a slight pivotal movement.

The horizontal head 35^a of the bracket 35 is pierced by a plurality of fastening devices such as bolts 40 which are adapted to pass through any pair of the series of apertures 32, 33 or 34 formed in the bracket plate 30 and thus adjustably secure the intermediate bracket 35 to the bracket plate 30. Dowel pins 41, diagonally opposed upon the bracket head 35^a are provided to enter the openings 42 piercing the bracket plate 30 adjacent to the series of apertures 32, 33, 34 to insure the proper positioning of the intermediate bracket 35, and the guide carried thereby. The corner of the plate 23 on the side of the member opposite to that upon which the member 24 is located and at the entrance end of the work guide is deflected or bent upwardly as at 43 to insure the positive entrance of the work into the guide.

From the foregoing description it will readily be understood that as the head 29^a is swung in one of its three adjusted positions the stapling mechanism 13 carried thereby therefore will change its position relative to the bar 11. Inasmuch as the stapling mechanism 13 must constantly be vertically aligned with one of the anvils or clencher blocks carried by the bar 11, it is necessary to adjust the bar 11 through the instrumentality of the screw 12. This movement of the bar 11 naturally causes the anvil or clencher block 26 of the work guide to be thrown out of vertical alignment with the stapling or stitching mechanism 13 and with the bar 11. Therefore, it is essential, in order to have the anvils or clencher blocks on the bar 11 in alignment with the stapling mechanism 13 and the clencher block or anvil 26, to shift or adjust the guiding mechanism 22 to conform with the adjustment of the head 29^a. This is done by positioning the fasten-

ing devices 40 in the proper set of the three pairs of openings 32, 33 or 34 provided in the work plate 30, and also positioning the dowel pins 41 in the proper openings 42.

- 5 It will be noticed that the openings 32, 33 and 34 are obliquely arranged in the bracket plate 30 and that there are as many pairs of openings as there are adjustments to the head 29^a. These openings 32, 33 and 34 are 10 so spaced from each other that the successive positioning of the intermediate bracket 35 to each pair of openings will aline a clencher block on the bar 11 with the clencher block or anvil 26 and the stapling 15 mechanism 13 after each successive adjustment of the head 29^a and the bar 11.

The work is fed into the guide in the manner shown in Fig. 4 and in dotted lines in Fig. 2, so that one edge of one flap will 20 engage the web 24 and this will force the folded edge of the work against the gage 19. The work is also arranged with respect to the guide so that the upper plate or member 23 will pass between two of the flaps. 25 When the overlapping flaps are advanced with respect to the work guide, they will pass over the clencher block 26 while other portions of the work will pass between the work guide and the arm 11. When the 30 stapling mechanism is operated, a staple will be inserted through the overlapping flaps and will be clenched by striking the clencher block 26. In order to accommodate the work guide for the movement of the 35 staple driving mechanism, the work guide is pivotally supported as above described so that the guide will yield slightly to permit the staple to be clenched by forcing the extremity of the work-supporting bar 22 40 downwardly toward the arm 11, the work guide thereby yielding to the operation of the stapling mechanism. With this construction, it will be manifest that all vibration of the work guide will be dispensed 45 with. If desired, another gage 45 similar to the gage 19 may be provided on the other side of the work guide for directing and properly positioning another section of the work with respect to the stapling mechanism 50 when two separate sections are secured together by overlapping portions of the edges of the sections and fastening them together by the stapling mechanism.

What is claimed as new is:

- 55 1. The combination with a support, of a head carried thereby for adjustment, a work support adjustable to correspond to the adjustments of said head, a work guide arranged to be alined with the head and work 60 support, and means whereby said guide may be bodily adjusted to predetermined positions which correspond to the various adjustments of the head and work support. 65 2. In a machine for stitching overlapping flaps, the combination of a guide member for

the work, embodying spaced members connected adjacent one edge, one of said members serving to space apart the flaps, the other member comprising a work supporting bar, a clencher block arranged on the said 70 bar, a support arranged above the work guide, and means connecting the work guide with the last recited support for bodily adjustment and for free pivotal movement with respect thereto. 75

3. In a machine for stitching overlapping flaps, the combination of a guide member for the work embodying spaced members connected adjacent one edge, one of said members serving to space apart the flaps, the 80 other member comprising a work supporting bar, a clencher block arranged on the said bar, a support arranged above the work guide, and means connecting the work guide with the last recited support for free pivotal 85 movement with respect thereto about a substantially horizontal pivot.

4. In a machine for stitching overlapping flaps, the combination of a guide member for the work embodying spaced members 90 connected adjacent one edge, one of said members serving to space apart the flaps, the other member comprising a work supporting bar, a clencher block arranged on the said bar, a support arranged above the work 95 guide, means connecting the work guide with the last recited support for free pivotal movement with respect thereto and about a substantially horizontal pivot, and means for limiting such pivotal movement. 100

5. In a machine for stitching overlapping flaps, the combination of a guide member for the work, embodying spaced members connected adjacent one edge, one of said members serving to space apart the flaps, 105 the other member comprising a work supporting bar, a clencher block arranged on the said bar, a support arranged above the work guide, and means connecting the work guide with the last recited support for pivotal movement with respect thereto and about a substantially horizontal pivot, the 110 said means also embodying means whereby the work guide may be bodily adjusted with respect to the last recited support and secured in its adjusted position. 115

6. In a machine for stitching overlapping flaps, the combination of a work guide, a clencher block arranged on the guide, a support above the guide, a bracket adjustably 120 connected with the support, and means connecting the guide with the bracket for free pivotal movement with respect thereto.

7. In a machine for stitching overlapping flaps, the combination of a work guide, a 125 clencher block arranged on the guide, a support above the guide, a bracket adjustably connected with the support, means connecting the guide with the bracket for free pivotal movement with respect thereto, toward 130

and away from the support, and means for limiting such pivotal movement.

8. In a machine for stitching overlapping flaps, the combination of a work guide, a 5 clencher block arranged on the guide, a support above the guide, a bracket adjustably connected with the support, means connecting the guide with the bracket for free 10 pivotal movement with respect thereto, and 15 on a substantially horizontal pivot, and a pin and slot connection between the guide and bracket for limiting such pivotal movement.

9. The combination with an adjustable 15 stapling head, of a primary bracket carried thereby, a secondary bracket attached to said primary bracket for relative bodily adjustment whereby said secondary bracket may be adjusted to correspond to the 20 adjustments of said head, and a work guide carried by said secondary bracket.

10. In a machine for stitching overlapping flaps, the combination of a main work support, a guide member for the work embodying spaced connected members, one of 25 said members serving to space apart the flaps, the other member comprising a work supporting bar and being spaced above the main work support, a clencher block ar- 30 ranged on the said bar, a support for the stitching mechanism arranged above the work guide, and means connecting the work guide with the last recited support for bodily adjustment and for free pivotal 35 movement with respect thereto.

11. In a machine for stitching overlapping flaps, the combination of a main work support, a guide member for the work embodying spaced connected members, one of 40 said members serving to space apart the flaps, the other member comprising a work supporting bar and being spaced above the main work support, a clencher block ar- 45 ranged on the said bar, a support for the stitching mechanism arranged above the work guide, and means connecting the work guide with the last recited support for bodily lateral adjustment with respect thereto and also for free pivotal movement about 50 a substantially horizontal pivot.

12. In a machine for stitching overlap-

ping flaps, the combination of a main work support, a guide member for the work embodying spaced connected members, one of 55 said members serving to space apart the flaps, the other member comprising a work supporting bar and being spaced above the main work support, a clencher block ar- 60 ranged on the said bar, a support for the stitching mechanism arranged above the work guide, and means connecting the work guide with the last recited support for bodily lateral adjustment with respect thereto, and also for free pivotal movement about a substantially horizontal pivot. 65

13. In a machine for stitching overlapping flaps, the combination of an adjustable main work support, a guide member for the work embodying spaced connected members, one of 70 said members serving to space apart the flaps, the other member comprising a work supporting bar and being spaced above the main work support, a clencher block ar- 75 ranged on the said bar, a support for the stitching mechanism arranged above the work guide; means connecting the work guide with the last recited support for bodily lateral adjustment with respect thereto, and also for free pivotal movement about a substantially horizontal pivot, and 80 means for adjusting the said main support laterally and in a direction transverse to the direction of pivotal movement of the guide.

14. The combination with a swivel head, 85 of a stitching mechanism carried thereby, a work guide coöperating with said head and having a clencher block or anvil at the terminal thereof, and means for adjusting said work guide to accommodate the positions of said head and constantly aline the 90 clencher block or anvil and the stitching mechanism aforesaid irrespective of the adjustment of said head.

In testimony whereof I have signed my name to this specification, in the presence of 95 two subscribing witnesses, on this 5th day of February, A. D. 1912.

HENRY WEBER.
